UNITED STATES PATENT OFFICE.

CLARENCE P. GALLISTEL, OF CHICAGO, ILLINOIS, ASSIGNOR TO MID-WEST BOX COMPANY, OF CHICAGO, ILLINOIS, A CORPORATION OF INDIANA.

SHIPPING BOX FOR ARTICLES.

Application filed June 17, 1925. Serial No. 37,617.

The invention relates to shipping cases for articles, such as books.

The object of the invention is to provide an improved shipping case for books or similar articles, which is adapted to be formed of a single sheet of corrugated board, and in which provision is made for effectively cushioning the ends of the books, or articles.

10 The invention consists in the several novel features hereinafter set forth and more particularly defined by the claims at the conclusion hereof.

In the drawing: Fig. 1 is a plan of the 15 shipping case before the flaps have been folded around the book or article. Fig. 2 is a perspective showing the cushion forming flaps in operative position and the other flaps open. Fig. 3 is a transverse section, 20 and Fig. 4 a longitudinal section.

The invention is exemplified in a blank 25 which is formed of a single piece of double-faced corrugated board, and is composed of a member 5 which is adapted to form the bottom or one side of the case and to enclose one side of a book; side flaps which 30 comprise members 6 adapted to protect and enclose the front and back of the book, and members 7 adapted to fold over the other side of the book, the edges of members 35 7 being adapted to meet when folded over, as shown in Fig. 3, to completely cover said other side of the book; and end flaps, each of which comprises a member 8 adapted to 40 form an outer end wall, a member 9 adapted to extend inwardly under one of members 7 of the side flaps, a member 10 adapted to be folded into parallel relation with the member 8, and an end member 11 adapted to extend outwardly to abut against the member 8. Longitudinal creases 12 and 13 are 45 formed between the members 6 and 5 and 7, so that the side flaps will readily fold on the proper lines. The blank is also creased transversely at 14, 15 and 16, to cause the members of the end flaps to be readily foldable into the positions described.

In shipping books and the like, it is important that the top and bottom thereof 50 should be properly cushioned and protected against possible injury, and by providing end flaps, which are foldable, as illustrated and disposed to form box-like formations,

the top and bottom of the book receives effective protection. Usually the corrugations extend longitudinally of the side flaps, and transversely of the end flaps. When the end flaps are folded into this box-like formation, the top and bottom of the book will be spaced inwardly from the outer wall members 8 and thus held against possible injury in shipment. The end of member 11 abuts against the inner face of the member 8, so that each member 10 will be properly spaced from the member 8 and protected, notwithstanding any possible damage to said member 8. When the side flaps are folded into closed position, as shown in Fig. 3, a sealing strip 17 will be applied to hold them closed. Members 7, when closed, will overlie the 70 members 9 of the hollow end protectors, so that no special means for holding the protectors in operative position will be necessary.

The invention exemplifies a corrugated board shipping case which is formed of a single sheet, which can be produced at a low cost, and which, when closed, will serve to effectively protect the book against damage in shipment.

The invention is not to be understood as restricted to the details set forth, since these may be modified within the scope of the appended claims, without departing from the spirit and scope of the invention.

While the invention has been described as adapted for the shipment of books, it is to be understood that it may be used for other articles, for which it is adapted.

Having thus described the invention, what I claim as new and desire to secure by Letters Patent, is:

1. A shipping case for a book or similar article consisting of a single sheet of paper board and comprising a rectangular member adapted to enclose one side of the book, a pair of flaps connected to the side margins of the member and adapted to be secured and folded together to enclose the front and back and the other side of the book, and a pair of flaps connected to the bottom and top margins of said member and adapted to space the side forming portions apart and be folded to enclose and form hollow engagement-cushions for the top and bottom of said book, each of said last mentioned flaps

- being provided with portions adapted to be folded to form inner and outer walls, a connecting wall between the inner and outer walls and adapted to underlie the side forming portions of said first mentioned flaps, and a spacing wall between said inner and outer walls, the flaps being creased so that their several portions will fold correctly into operative position.
- 5 10 2. A shipping case for a book or similar article consisting of a single sheet of corrugated board and comprising a rectangular member adapted to enclose one side of the book, a pair of flaps connected to the side margins of the member and adapted to be secured and folded together to enclose the front and back and the other side of the book, and a pair of flaps connected to the bottom and top margins of said member and
- 15 adapted to space the side forming portions apart and be folded to enclose and form hollow engagement-cushions for the top and bottom of said book, each of said last mentioned flaps being provided with portions adapted to be folded to form inner and outer walls, a connecting wall between the inner and outer walls and adapted to underlie the side forming portions of said first mentioned flaps, and a spacing wall between said inner and outer walls, the flaps being creased so that their several portions will fold correctly into operative position, the corrugations of the board extending transversely to the creases in the said last mentioned flaps.

Signed at Chicago, Illinois, this 4th day 35 of June, 1925.

CLARENCE P. GALLISTEL.
